PORATION OF NEW YORK

TELEPHONE TRANSMITTER

Application filed March 6, 1929, Serial No. 344,774, and in Great Britain July 28, 1928.

This invention relates to telephone transmitters and more particularly to transmitter mouthpieces of the hygienic type.

An object of the invention is to improve the acoustic properties of mouthpieces for telephone transmitters.

Various attempts have been made to produce transmitter mouthpieces of hygienic pattern which comprise a smooth outer surface which can be easily kept clean. To this end, spherical and other shapes of mouthpieces have been provided, slots or other shaped passages being formed in the shell for the purpose of allowing sound waves to enter.

It has been found, however, that owing to the relatively large hollow space in the interior of such mouthpieces they have very poor acoustic properties. The present invention therefore aims to provide an improved form of such hygienic type of mouthpiece in which the above disadvantages are overcome.

In accordance with the present invention a substantially solid mouthpiece having a smooth outer surface is provided with one or more sound passages therein communicating with a passage which is arranged to direct the sound waves onto the transmitter diaphragm. Preferably the first mentioned passages are in the form of slots which communicate with a cylindrical central passage transverse to the slots. The said passages with the transmitter are preferably proportioned in such a manner as to form a mechanical filter.

According to another feature of the invention means is provided to seal the joint between the central passage in the mouthpiece and the transmitter proper.

Examples according to the invention are illustrated in the accompanying drawing in which Fig. 1 is a sectional diagram illustrating a portion of a handset with a spherical mouthpiece. Fig. 2 is a sectional diagram illustrating a modified form of mouthpiece. Fig. 3 is a face projection of the mouthpiece shown in Fig. 2, and Fig. 4 is a transverse section showing the arrangement of the slots.

It will be seen from the drawing that the

mouthpiece according to this invention comprises a substantially solid dome-shaped moulding 1, having a smooth outer surface broken only by the slots 2 which communicate with a central passage 3 which is arranged to direct the sound waves from the slots onto the transmitter diaphragm.

The cross-sectional area of the slots 2 is arranged to be substantially equal to the cross-sectional area of the central passage 3 and in order that the junction between the said slots and passage may be effective without any throttling action it will be noted that the outer edges of these slots are carried down and converge into the central passage in a stepped formation.

The central passage preferably makes a sound tight joint with the transmitter proper and for this purpose suitable washers may be provided on the lip 4. The central passage 3 may be cylindrical or slightly conical in order to facilitate moulding.

As indicated in Fig. 1 a gauze lining 5 may be provided for the central passage in order to prevent particles which may have found their way into the slot 2 from entering the transmitter. This lining may have an outwardly directed rim as indicated at 6 on which the sealing washers 7 may be located. The washers make a sound tight joint between the apertured plate 8 associated with the transmitter 9, the floating diaphragm 10 being arranged behind the plate and forming the driving member for the granules in the chamber 11.

It will be seen that with the construction herein described a mouthpiece of very simple form and one which may be readily moulded, is obtained. Moreover, the mouthpiece possesses considerable strength and is of improved acoustic properties owing to the absence of large hollow spaces within it.

What is claimed is:

1. A transmitter comprising a casing, a diaphragm within said casing, and a substantially solid dome-like mouthpiece attached to said casing, said mouthpiece having long narrow sound passages therein communicating with a central cylindrical passage arranged to direct sound waves onto said diaphragm.

2. A transmitter comprising a casing, a diaphragm within said casing, and a substantially solid dome-like mouthpiece attached to said casing, said mouthpiece having sound passages therein communicating with a central passage, said sound passages being in the form of slots which enter the central passage substantially at right angles.
3. A transmitter according to claim 2 in which the cross-sectional area of the slots is substantially equal to the cross-sectional area of the central passage, the junction between said slots and passage being effected without throttling.
4. A transmitter comprising a casing, a diaphragm within said casing, a substantially solid dome-like mouthpiece attached to said casing and having a central passage therein, and a sealing member between said mouthpiece and said diaphragm adjacent said central passage.
5. A transmitter comprising a casing, a diaphragm within said casing, a substantially solid dome-like mouthpiece attached to said casing having a central passage therein, an apertured plate between said diaphragm and mouthpiece, and a sealing member carried by said mouthpiece and engaging said apertured plate.
6. A transmitter comprising a casing, a diaphragm within said casing, a substantially solid dome-like mouthpiece attached to said casing, said mouthpiece having sound passages therein communicating with a central passage, and a hollow gauze lining in said central passage of said mouthpiece.
7. A transmitter comprising a casing, a diaphragm within said casing, a substantially solid dome-like mouthpiece attached to said casing and having sound passages therein communicating with a central passage, and a gauze lining in said central passage, said lining having an outwardly extending rim held between said mouthpiece and said diaphragm.
8. A transmitter comprising a casing, a diaphragm within said casing, a substantially solid dome-like mouthpiece attached to said casing having a central passage therein, an apertured plate between said diaphragm and mouthpiece, and a sealing ring clamped between said mouthpiece and said apertured plate.
9. A transmitter comprising a casing, a diaphragm within said casing, a substantially solid dome-like mouthpiece attached to said casing, said mouthpiece having slits therein communicating with a central passage, and a cylindrical gauze lining in said central passage of said mouthpiece.

In witness whereof, we hereunto subscribe our names this 6th day of February, 1929.

LYNDALL C. POCOCK.
REGINALD BLACKBURN.
